(57) **CLAIM**

We claim, the ornamental design for handle, as shown and described.

DESCRIPTION

FIG. 1 is a perspective view of the handle of the present invention.

FIG. 2 is a bottom view of the handle of FIG. 1.

FIG. 3 is a side view of the handle of FIG. 1, the opposite side view is a mirror image of FIG. 3.

FIG. 4 is a front view of the handle of FIG. 1; and,

FIG. 5 is a left top view of the handle of FIG. 1.

The broken lines in FIGS. 2 and 5 form no part of the claimed design.
